Primary Examiner — George D. Kirschbaum

(21) Appl. No.: **29/804,545**

Assistant Examiner — Lillian Embrey

(22) Filed: **Aug. 20, 2021**

(74) Attorney, Agent, or Firm — Trojan Law Offices

(51) LOC (14) Cl. **23-01**

(57) **CLAIM**

(52) **U.S. Cl.**

The ornamental design for an automated watering device for plants, as shown and described.

USPC **D23/215**

DESCRIPTION

(58) **Field of Classification Search**

USPC D23/213, 214, 215, 261, 413; D10/56, D10/96; D8/1; D7/400

CPC .. A01G 27/003; A01G 27/00; A01G 13/0212; A01G 27/005; A01G 27/06; A47G 2033/1286; A47G 2033/1293

See application file for complete search history.

FIG. 1 is a front perspective view of an automated watering device for plants;

FIG. 2 is a front perspective view of an automated watering device for plants of FIG. 1;

FIG. 3 is a bottom perspective view of an automated watering device for plants of FIG. 1;

FIG. 4 is a front view of an automated watering device for plants of FIG. 1;

FIG. 5 is a back view of an automated watering device for plants of FIG. 1;

FIG. 6 is a left side view of an automated watering device for plants of FIG. 1;

FIG. 7 is a right side view of an automated watering device for plants of FIG. 1;

FIG. 8 is a top view of an automated watering device for plants of FIG. 1; and,

FIG. 9 is a bottom view of an automated watering device for plants of FIG. 1.

The broken lines are included for the purpose of illustrating a water tank attachment and forms no part of the claimed design.
